UNITED STATES PATENT OFFICE.

FREDERICK J. FLAHERTY, OF WOODSTOCK VALLEY, CONNECTICUT, ASSIGNOR, BY MESNE ASSIGNMENTS, TO WELTE-MIGNON CORPORATION, OF NEW YORK, N. Y., A CORPORATION OF DELAWARE.

COMBINATION STOP MECHANISM FOR ORGANS AND THE LIKE.

Application filed June 4, 1925. Serial No. 34,972.

In an application executed by me of even date herewith and numbered serially 34,971 I have shown, described and generically claimed three embodiments of combination 5 stop actions.

The present application has particular relation to one of the embodiments shown, described and generically claimed in the aforesaid application, namely, to that particular 10 embodiment of the invention in which the slides have two distinct phases of movement in the same direction imparted to them by manually operable plungers or other suitable devices connected to the slides, respectively, 15 by mechanical means instead of by means of an electro-pneumatic nature, and in which there are stop means which are yieldably pressed into the path of said slides to be engaged thereby at the places at which the 20 movements of the slides, respectively, for the playing operations are completed and which move with said slides during the remainder of the travel of the latter for the setting operation, until their movement and the 25 movement of the corresponding slides are stopped by a wall of the enclosing structure.

In the accompanying drawings wherein like characters of reference denote corresponding parts in the several views:—

30 Fig. 1 is a perspective view of the particular embodiment upon which this invention is founded.

Fig. 2 is a front view partly in section of one end of the combination stop action.

35 Fig. 3 is a view on the line 3—3 of Fig. 2.

Fig. 4 is a detail view to illustrate the preferred mechanical connection between the manually operable controlling member and its corresponding combination operating 40 element.

10-14, inclusive, designate stop keys which may be of any suitable kind, the ones illustrated being the pivoted tablets now preferred for use in the modern pipe organ. 45 These stop keys are individually pivoted up on a common stationary shaft 15 so as to be severally movable about the shaft into "on" or "off" position, by the organist. They govern communication of the sets or groups 50 of tone emitting elements, couplers, tremulants etc., respectively, with the wind system of the organ, it being understood in this connection that when the outer end of any tablet

is depressed to its "on" position the particular stop controlled thereby is operative 55 and that when the outer end of said tablet is raised to its "off" position the particular stop controlled thereby is inoperative.

Since the tone emitting elements, couplers, swells etc., through which they have communication with the wind system of the organ and the means operable under control of the stop keys to control said means of communication form no part of the present invention and are well known in the art, they 65 have not been herein illustrated and need not be particularly described.

Each stop key is provided, as usual, with a spring *x* (shown best in Fig. 3) operatively related thereto to throw the key to either its 70 "on" or "off" position when it has passed a position midway between the two, these springs thereby operating to hold the keys against accidental displacement from their set positions, either "on" or "off".

It will, of course, be understood that the 75 number of stops and stop keys varies in different organs and that each stop included in the organ will have its appropriate stop key, and, further, that wherever the term stop or 80 stop keys is used herein, it is intended to include not only those stops which have reference to speaking pipes or tone emitting elements, but also to the mechanical stops, as 85 swells, couplers etc., which may be incorporated in the instrument.

A series of shafts 16 corresponding to the 90 respective stop keys have their outer ends suitably connected to the inner ends of the latter, the means shown for this purpose comprising cranks 17 and links 18. Each of 95 these shafts is provided along its length with a series of actuators B, each comprising two complementary members, marked 19 and 20, respectively. One member, as 19, of each actuating element is fixed on its shaft 16 and the other member, 20, is supported by said shaft and has pivotal movement relatively thereto.

Each of these actuators also has at each of 100 its ends a means indicated at *b*, *b'* operative automatically to releasably lock their corresponding ends to each other when said ends have been brought into juxtaposition: suitable means for this purpose comprising cup-shaped recesses and corresponding projec-

tions adapted to interengage when in registering position and to be disengaged by pressure applied to move one member relatively to one and corresponding depressions b' in 5 the other. It is preferred in practice that each member 19 be composed of two sides spaced from each other to receive the complementary member 20 between them. Attention is called to the fact that the members 10 19 and 20 of each actuator are relatively so shaped that between the two extremes of their relative movement they will be free from any locking engagement one with the other and when at either extreme of their 15 relative movement they will be locked to each other at the corresponding end of the actuator and free from engagement with each other at the other end of the actuator.

It will be understood that there is a shaft 20 16 for every stop key, and that each shaft is so connected with the corresponding stop key that the shaft and its stop key will rock synchronously whenever rocking movement is imparted either to the stop key by the 25 finger of the organist on said key or by pressure applied to the appropriate actuator B.

Pressure is applied to the actuators to move the corresponding stop keys by a 30 means which includes combination operating elements here shown as a series of slides A, each of which comprises two members 21 and 22 arranged on opposite sides of all of the shafts 16 and connected with each other for 35 unitary movement, as by the end strips 23 and 24. The number of these slides varies in accordance with the number of different combinations which the instrument is constructed to provide for at any one time. 40 Each slide is suitably pressed resiliently outward, as by means of a spring such as shown at X in Fig. 2. Each has one of its longitudinal members provided with a series of lateral projections 25 and its other longitudinal member provided with a like series of 45 lateral projections 26. The series of projections 25, and also the series of projections 26, on each slide, correspond in number with the number of shafts 16, and the projections 50 25 are operatively related to one end of the respective actuators B while the projections 26 are operatively related to the other ends of said actuators. The co-operative action of the projections and actuators will be hereinafter set forth. In the construction illustrated each slide A is formed of a flat plate and a longitudinal member 27 of greater thickness than the plate: said plate having a longitudinal opening 28 bounded by the 55 members 21 and 22 and end strips 23 and 24 and said longitudinal member 27 being preferably of rounded cross section and fixedly secured to the lower edge of the plate and having an end portion or member, 29, projecting outwardly therefrom beyond the ver-

tical plane of the end 24 of the plate. In the illustrated construction the projection 29 of the several slides form bearing elements through which the respective slides have their inner ends supported by an inner wall 70 D of the chamber in which the action is mounted. This wall is pivoted at d.

In the operation of preparing a combination, the particular slide A which has been selected to operate the combination is moved 75 inward relatively to the actuators B to place the slide A in such position with relation to the corresponding actuators B that its projections will substantially engage the protruding ends of the members 20 of said actuators.

While the parts are in this position, the outer ends of the stop keys corresponding to the particular stops which are to come "on" are pressed downward to their fullest extent, while the outer ends of the stop keys 85 which are to go "off" under control of this slide are pressed up to their fullest extent, and the outer ends of those keys which are to be "neutral" in this particular combination, are moved to a mid-position. The described movement of the key or keys corresponding to the stop or stops which are to come "on" turns the corresponding shaft or 90 shafts 16 and actuator-members 19 and since the members 20 of said actuators are held by the projections 25, 26 against movement at this time, it follows that the lower ends of the actuator-members 19 will be brought into juxtaposition with the lower ends of the actuator-members 20. The parts are so correlated that at the end of this movement of the stop key or keys the holding elements b , b' at the lower ends of the corresponding actuator-members will snap into engagement 95 with each other so as to hold these ends together. The described movement of the key or keys corresponding to the stops which are to go "off" under control of this particular slide, turns the corresponding shaft or shafts 100 16 and actuating member or members 19, 110 relatively to the corresponding member or members 20 and causes these members to be locked together at their upper ends instead of at their lower ends: and the described movement of stop key or keys to mid-position places the slide and the actuator or actuators corresponding to the keys so moved, in such relation that no movement of the slide will be communicated to said 115 actuators.

By way of concrete examples: let us assume that the organist desires to prepare three different combinations of the stops controlled by the stop-keys marked 10-14, inclusive, in Fig. 1 of the drawing and that in one of these combinations, identified as "first combination", the stops controlled by keys 10 and 12, are to come "on" while the stops controlled by keys 11, 13 and 14 are to go "off" when the particular slide A 120 130

selected to operate this combination is actuated; while in another combination, identified as "combination No. 2", the stops controlled by keys 10, 11 and 13 are to 5 come "on" and the stops controlled by keys 12 and 14 are to go "off" when the particular slide A selected for this operation is operated; and in still another combination, identified as "combination No. 3", the stops controlled by key 10 is to remain "neutral", while the stops controlled by keys 12 and 14 are to come "on" and the stops controlled by keys 11 and 13 are to go "off": the organist in preparing these combinations, proceeds as 10 follows:

The particular slide which is to operate the "first combination" is moved inward and while in said position the organist presses the outer ends of stop keys 10 and 12 downward as far as they will go and all other stop 20 keys upward as far as they will go: in preparing "combination No. 2" he similarly presses the outer ends of stop keys 10, 11 and 13 downward and the remaining stop keys 25 upward, while the slide which controls this combination is in its inner position; and in preparing "combination No. 3" he places stop key No. 10 in a mid-position, presses stop keys Nos. 12 and 14 downward to their 30 fullest extent and stop keys 11 and 13 upward to their fullest extent, while the selected slide is in its inner position. As already described, in preparing the first combination the members 19 and 20 of the 35 actuators corresponding to keys 10 and 12 were locked to each other at their lower ends, while the members 19 and 20 of the actuators corresponding to keys 11, 13 and 14 were locked to each other at their upper ends; and 40 that in preparing combination number 2, the actuators corresponding to keys 10, 11 and 13 have their members 19 and 20 locked to each other at their lower ends, while the similar members of the actuators corresponding to keys 12 and 14 are locked together at 45 their upper ends; and that in preparing combination No. 3 the members of the actuators corresponding to keys 12 and 14 are locked together at their lower ends, the members 50 corresponding to keys 11 and 13 are locked to each other at their upper ends, while the members of the actuators corresponding to key 10 will be free from each other at both ends of said actuator.

55 Of course, it will be understood that when each combination has been prepared the slide which has been selected to operate said combination and which was held inward while the combination was being prepared, is released and thereupon will be returned to its outer position by its spring X.

From the foregoing it will be clear that if the particular slide selected to operate or control the "first combination" be thereafter 60 pressed inward it will act upon the lower,

locked together, ends of the actuators corresponding to keys numbers 10 and 12 and upon the upper, locked together, ends of the actuators corresponding to keys 11, 13 and 14 in such manner as to cause the stops corresponding to keys 10 and 12 to speak, and the others to discontinue speaking, if they were "on" or to remain "off" if they were already "off", it, of course, being understood that in this operation the keys 10 and 12 are 70 moved to their "on" position and the keys 11, 13 and 14 moved to their "off" position, if "on" at this time, by the co-operative action of the said slide and actuators; and similarly that when in the playing of the organ the 75 particular slide selected to operate the control combination No. 2 is moved inward it will act upon the lower, locked together, ends of the actuators corresponding to keys 10, 11 and 13 in such manner as to bring said 80 keys into "on" position and upon the upper locked together ends of the actuators corresponding to keys 12 and 14 to move them to "off" position; and, finally, that when the 85 slide selected to operate or control combination No. 3 is moved inward by the organist to bring this combination into operation, stop keys 12 and 14 are lowered to "on" position and stop keys 11 and 13 are raised to "off" position, by the co-operative action of 90 said slide and the actuators corresponding to said keys, while the slide will have no effect whatever upon the actuators corresponding to key 10 and hence the stop controlled by said key will remain "on" if already "on" or 95 "off" if it was off at this moment.

As thus far described the invention is identical with parts shown, described and claimed in my companion application, Serial No. 34,971, the parts which constitute the 100 novel features of this invention, as already stated, having to do with a means for operating each slide without the intervention of power pneumatics or electrical controls.

This means comprises a plunger 100 for 110 each slide, connected with the latter by a bell crank lever, one arm (101) of which is pivoted to the inner end of a projection 100' from the plunger, and the other arm (102) of which is pivoted to one end of an arm 103 115 whose other end is pivoted, at 104, to an end of the corresponding slide A. Each bell crank lever is pivoted at 105 to an appropriate part of the organ structure.

It is beneficial, particularly in a construction such as that herein exemplified which contains provision for a "neutral" setting, to provide for an extent of travel of each slide in the combination-setting operation additional to that thereafter required in 120 bringing the stops into "on" or "off" position. The additional extent of travel in the setting operation will avoid all liability of any "fluttering" of those stops which are in neutral position when a combination slide 125 130

is operated for a playing operation, and since in such case means should be employed to define the phases of inward movement of the slides, there may be and preferably is employed for the latter purpose, a stop means, as the wall D, resiliently pressed forward, by a spring or springs 201, into the path of rearward movement of the slide. The correlation of the slide and stop is such that when the slide and stop are both in their forward positions, they will be separated a distance which permits the slide to traverse a first phase of inward movement in the setting operation, before it comes into contact with the stop, the second phase of inward movement of the slide then requiring greater force to overcome the tension of the spring or springs 201. Contact of the slide with the wall D thus indicates the end of the first phase of inward movement of the slide.

In the particular construction exemplifying this embodiment of the invention, the stop D is pivoted at its upper end, at d, and the inner end of the slide member has a shoulder 203 to engage the stop.

It is apparent that there may be one stop common to all the slides, or a separate stop for each slide, as desired. In other words, the stop may be a continuous member, different portions of whose length are in operative relation with the slides, respectively, or in lieu of such continuous member, there may be employed a series of independently movable stops for the series of independently movable stops for the series of independently movable slides, respectively.

It will also be apparent that the construction illustrated is merely exemplary and that the details may be variously changed and the invention otherwise and variously embodied without departure from its spirit as defined by appended claims.

For example: any means suitable to impart the necessary movements to the respective slides may be employed in lieu of the plungers 100 and their illustrated connections to the slides, it being particularly noticeable in this connection that separate operating elements may be provided for the respective two movements of each slide, instead of one operating element (plunger 100) for both movements, if preferred.

Having thus described the invention what I believe to be new and desire to secure by Letters Patent, is:—

1. A combination stop action for organs or the like comprising combination setting and operating means including a movable member whose path of travel in the setting operation is different from that in the operation of the combination and means operatively related to said movable member to indicate the place in its travel at which the

combination corresponding to said member is operative.

2. A combination stop action for organs or the like comprising combination setting and operating means including a movable member whose limits of travel in the setting operation are different from those in the operation of the combination and means operatively related to said movable member to indicate the said limits of its travel.

3. A combination stop action for organs or the like comprising combination setting and operating means including a movable member whose limits of travel in the setting operation are different from those in the operation of the combination and a yieldable member movable within defined limits and operatively related to said movable member to indicate the said limits of its travel.

4. A combination stop action for organs or the like comprising combination setting and operating means including a movable member whose path of travel in the setting operation includes and extends beyond its path of travel in the operation of the corresponding combination for playing purposes, and a member operatively related to said movable member to indicate the point reached by the latter to cause the operation of the corresponding combination.

5. A combination stop action for organs or the like comprising combination setting and operating means including a movable member whose path of travel in the setting operation includes and extends beyond its path of travel in the operation of the corresponding combination for playing purposes and a yieldable stop member arranged in the path of said movable member at a place to be engaged by the latter when the combination corresponding to said movable member is operative.

6. A combination stop mechanism for organs or the like comprising combination setting and operating means including a yieldable stop member normally spaced from and in the path of movement of a member of said means, to be engaged thereby when operating the combination and to have movement therewith in the setting of the combination.

7. A combination stop mechanism for organs or the like including a member having slidable movement when setting the combination and when operating the combination for playing purposes, and a yieldable stop member arranged in the path of movement of said slidable member and defining said movement when setting and when operating the combination.

8. A combination stop mechanism for organs or the like comprising combination setting and operating means including a slid- able member, a device connected to said

member to impart sliding movement thereto and a yieldable stop member arranged to be engaged by said member at the place in the travel thereof at which the corresponding combination is operative.

9. A combination stop mechanism for organs or the like comprising combination setting and operating means including a slideable member, a manually operable plunger 10 mechanically connected to said member to impart sliding movement thereto and a yieldable stop member to be engaged by said member at the place in the travel thereof at which the corresponding combination 15 is operative.

10. A combination stop mechanism for organs or the like, comprising actuators settable into "on" position, "off" position, or "neutral" position, and means including stop 20 keys and combination operating elements to set any of said actuators into position in which the corresponding stop will come on or go off under control of the combination operating elements or be unaffected by the 25 operation of the latter, said combination operating elements having different paths of travel in the playing and setting operations, respectively, and means respectively in the paths of travel of said elements, to indicate 30 the places in the travel of said elements at which the combination controlled thereby are operative.

11. A combination stop mechanism for organs or the like, comprising reversibly operative actuators, respectively, settable also 35 to a neutral position, relatively movable setting and operating elements operatively connected with each actuator, one of said elements having an extent of movement in the 40 setting operation greater than that for the playing operation, and a yieldable member to engage the latter element at the place where the movement of said element for the playing operation is completed.

45 12. A combination stop mechanism for organs or the like, comprising reversibly operative actuators, respectively, settable also to a neutral position, relatively movable setting and operating elements operatively connected with each actuator, one of said elements being slideable and having an extent of movement in the setting operation greater 50 than that for the playing operation, and a yieldable member arranged in the path of 55 the latter element at the place where the movement of said element is completed and movable therewith throughout the remainder of its movement, for the setting operation.

60 13. A combination stop mechanism for organs or the like comprising combination setting and operating means including a movable member whose path of travel in the setting operation is different from that in the operation of the combination, a manually 65 operable plunger, mechanical connections

between said plunger and the movable member and means to press the movable member and plunger resiliently outward.

14. A combination stop mechanism for organs or the like comprising combination setting and operating means including a movable member whose path of travel in the setting operation is different from that in the operation of the combination, a manually operable plunger, mechanical connections 70 between said plunger and the movable member, means to press the movable member and plunger resiliently outward and a yieldable stop member operatively related to the movable member to indicate by the additional 75 pressure required to overcome its tension the place in the travel of said movable member at which the combination corresponding to said member is operative.

15. A combination stop mechanism for organs or the like including a member having slideable movement in one direction when setting the combination and in the same direction when operating the combination for playing purposes, a resilient means to move 80 said member in the opposite direction, operating means connected to said member and operative to move it against the tension of the resilient means, and a resilient stop 85 operatively related to said slideable member 90 to define its movement produced by operation of the operating means.

16. A combination stop mechanism for organs or the like including a member having slideable movement in one direction when 100 setting the combination and in the same direction when operating the combination for playing purposes, a resilient means to move said member in the opposite direction, a plunger, a mechanical connection between 105 the plunger and the slideable member, to impart sliding movement to the latter against the tension of the resilient means when the plunger is operated, and a resilient stop 110 operatively related to said slideable member 115 to define its movement produced by operation of the plunger and said connections.

17. A combination stop mechanism for organs or the like including a member having slideable movement in one direction when 115 setting the combination and in the same direction when operating the combination for playing purposes, a resilient means to move said member in the opposite direction, operating means connected to said member and 120 operative to move it against the tension of the resilient means, a pivoted stop member and a resilient means to hold the stop member in the path traversed by the slideable member in the setting of the combination 125 and in the operation of the combination for playing purposes.

In testimony whereof I affix my signature.

FREDERICK J. FLAHERTY.
